TELESCOPING AND ADJUSTABLE CRUTCH

Raymond W. Slater, Pawtucket, R. I.

Application February 18, 1950, Serial No. 144,994

1 Claim. (Cl. 135—50)

1

This invention relates to a crutch which may be readily adjusted as to length and handle position, and which may be substantially telescoped for transportation or storage.

It is one important object of the invention to provide a crutch in which an improved construction permits easier and more convenient adjustment of the crutch as to length and also as to handle position relative to the armpit rest.

A further object of my invention is to provide an improved construction by which the crutch may be quickly and easily collapsed or telescoped to small compass for transportation or storage.

My invention further relates to arrangements and combinations of parts which will be herein-after described and more partially pointed out in the appended claim.

A preferred form of the invention is shown in the drawings, in which

Fig. 1 is a longitudinal sectional view of my improved crutch;

Fig. 2 is a partial side elevation, looking in the direction of the arrow 2 in Fig. 1;

Fig. 3 is a side elevation, looking in the direction of the arrow 3 in Fig. 1;

Fig. 4 is a view similar to Fig. 1 but showing the crutch partially telescoped;

Fig. 5 is an enlarged side view, partly in section and showing the lower portion of the crutch;

Fig. 6 is an enlarged sectional view corresponding to the middle portion of Fig. 1;

Fig. 7 is a detail transverse section, taken along the line 7—7 in Fig. 6;

Fig. 8 is a detail partial side elevation, looking in the direction of the arrow 8 in Fig. 6;

Fig. 9 is a side elevation of a modified crutch handle; and

Fig. 10 is an end view, looking in the direction of the arrow 10 in Fig. 9.

Referring to Figs. 1 and 2, improved crutch comprises an upper tubular member 20, an intermediate tubular member 22 and a lower tubular member 24. The intermediate member 22 is slideable upward within the upper member 20 when released, and the lower member 24 is similarly slideable upward within the intermediate tubular member 22 when released. The telescoped position of the parts is indicated in Fig. 4.

An armpit rest 30, commonly of wood, is secured to the upper end of the tubular member 20 in any convenient manner, as by a plate 31 screwed to the under side of the rest 30 and having a hub portion 32 extending into the tubular member 20 and secured therein by a cross bolt 33.

The lower end of the upper tubular member 20 is swaged or contracted, as indicated at 46, to slidably receive the intermediate tubular member 22. The upper end of the intermediate member 22 is expanded as indicated at 42 to slidably

2

fit the normal inside diameter of the member 20.

A relatively long coil spring 44 is mounted in the upper part of the tubular member 20 and engages the armpit rest hub 32 at its upper end and the upper end of the tubular member 22 at its lower end, as indicated in Fig. 6.

A handle 50 has a sleeve-like end portion 51 which is slideable on the outer surface of the upper tubular member 20. The member 20 has a series of preferably rectangular openings 52 (Fig. 6), shown as five in number and spaced axially in the lower end portion of the tube 20. Depressions 53 are made in the opposite side of the member 20 and in transverse alignment with the openings 52.

A plunger 54 is slideable axially in the handle 50 and has a preferably rectangular end portion 55 adapted to enter any one of the openings 52 with which it may be aligned. A setscrew 56 in the sleeve portion 51 may then be screwed into one of the depressions 53 to lock the handle in the selected position. Substantial and convenient adjustment of the handle 50 relative to the armpit rest 30 is thus available.

25 The tubular member 22 is provided with a longitudinal groove or keyway 60 (Figs. 2 and 7), and a pin or stud 61 in the contracted lower end portion 48 of the tubular member 20 extends into the groove 60 and acts as a key to prevent relative rotation of the tubular members 20 and 22. The member 22, throughout the major portion of its length, is provided with closely adjacent and preferably rectangular slots or openings 64 (Figs. 6 and 8), any one of which may be aligned with the selected recess 52 and the plunger end portion 55. The end portion 55 will then enter the selected opening 64, thus locking the tubular members 20 and 22 in a selected longitudinal relation.

30 The plunger 54 is forced inward by a spring 67 (Fig. 6) seated in a recess 68 in the outer end of the plunger and engaging a cap 69 threaded into the outer end of the handle 50. A slide 70 has a reduced portion 71 extending through a slot 72 in the outer end of the handle 50 and may be secured to the plunger 54 by pins 74. The plunger 54 may be moved outward by manual pressure on the slide 70, thus withdrawing the end portion 55 from the locus of the slots 64 when it is desired to change the relative adjustment of the tubular members 20 and 22. Such adjustment is readily accomplished while the crutch is in use by withdrawing the plunger 54 and pressing the armpit rest 30 downward or allowing it to be moved upward by the spring 44 while the plunger 54 is withdrawn.

35 When the armpit rest is at the desired height relative to the ground or other supporting surface, the slide 70 is released and the plunger 54 then locks the parts in selected longitudinal relation.

The lower tubular member 24 may be provided with the usual rubber crutch tip 80 and at its upper end is provided with an extension member 81. This extension member 81 comprises a body portion 82 slidable in the tubular member 22 and having a reduced upper shank 83 which is a snug fit in a short tube 84 which is also slidable in the tubular member 22. The parts 82 and 84 are preferably welded together. Below the body portion 82, the member 81 is of reduced diameter as shown at 85 and has a threaded portion 86. The part 85 is of the same diameter as the lower tubular member 24 and may be welded thereto. A further reduced shank 87 of the member 81 snugly aligns the parts 81 and 24. The threaded portion 86 fits a contracted and corresponding threaded portion 88 (Fig. 6) at the lower end of the tubular member 22.

A sleeve-like lock nut 90 (Fig. 5) is slidable on the lower member 24 and is threaded at its upper end as indicated at 91 to fit the threaded portion 86 on the extension member 81.

Having described the details of construction of my improved crutch, the use and advantages thereof are as follows:

When the crutch is to be assembled for use, as indicated in Figs. 1 and 3, the lower tubular member 24 is inserted in the intermediate tubular member 22 and from the upper end thereof. The parts 24 and 22 and the spring 44 are then inserted in the upper end of the member 20 before the armpit rest 39 is applied. The contracted portion 60 (Fig. 6) at the lower end of the member 20 prevents the member 22 from falling out of the member 20 when it is released and the contracted and threaded lower end portion 88 prevents the member 24 from falling out.

The lower end of the member 24 extends through the portion 88 and may receive the crutch tip 80. The spring 44 may be compressed and the plunger 54 may be released to hold these parts nested. The member 24 is then drawn out along the member 22 and the threaded portion 86 of the member 24 is screwed through and partly beyond the threaded lower end portion 88 of the member 22.

The lock nut 90 is then threaded onto the projecting part of the threaded portion 86, thus locking the parts 22 and 24 in operative relation.

The plunger 54 and screw 56 can then be moved outward to release the handle sleeve 51, which may then be adjusted upward or downward to correspond with the length of the user's arm. The plunger 54 may then be released to enter the selected one of the openings 52, and the screw 56 may be tightened to retain the adjustment.

The plunger 54 may then be again moved outward to permit relative longitudinal adjustment of the tubular members 20 and 22, and the armpit rest 39 may be pressed downward or allowed to move upward to bring the crutch to the desired over-all length, after which the plunger 54 is released and locks the parts in adjusted position.

It will be seen that this latter adjustment is readily accomplished while the crutch is in use and that it requires only one hand to release the plunger 54 and to permit the adjustment to be made.

When the crutch is to be telescoped for transportation or storage, the plunger 54 is withdrawn and the tubular member 22 is forced into the member 20 as far as it will go, whereupon the plunger 54 is released to retain the parts in telescoped position.

The lock nut 90 is then unscrewed from the

75 122,694

threaded portion 86 and is allowed to drop to the position shown in Fig. 5. The threaded portion 86 is then screwed upward entirely through the threaded portion 88 (Fig. 6) at the lower end of the member 22, after which the lower member 24 may be pushed upward into the members 20 and 22, as indicated in Fig. 4.

The entire crutch may thus be conveniently telescoped for transportation or storage.

In Figs. 9 and 10 I have shown a modification in which a flashlight 100 is mounted on a handle 50a and may be clamped thereon by a cap 102 corresponding to the cap 69 previously described. The flashlight 100 may contain the usual dry battery and may have a push-button 102a by which contact may be made and light projected downward through a lens 103. It is thus possible for the user of the crutch to illuminate the surface on which the crutch is to be placed without releasing his grip on the crutch handle.

Having thus described my invention and the advantages thereof, I do not wish to be limited to the details herein disclosed, otherwise than as set forth in the claim, but what I claim is:

25 A telescoping and adjustable crutch comprising upper and intermediate tubular members, a lower member, and a locking sleeve, said intermediate member having an internally threaded portion at its lower end and said lower member having an externally threaded portion in its upper part fitting said internally threaded portion of said intermediate member, said intermediate member above said internally threaded portion being of greater diameter than said externally threaded portion of said lower member, and said externally threaded portion of said lower member projecting substantially below the internally threaded portion of the intermediate member when the crutch is assembled, so that the lower part of said externally threaded portion is positioned to receive said locking sleeve, and the unthreaded part of said lower member below the externally threaded portion thereof being of as small diameter as the points of the threads of said internally threaded portion of said intermediate member, whereby said lower member is freely movable upward within said intermediate member for nesting when said locking sleeve is removed and when said externally threaded portion of the lower member is screwed upward entirely through said internally threaded portion of said intermediate member and clears said internally threaded portion.
